UNITED STATES PATENT OFFICE.

PHILIP H. CONE, OF CINCINNATI, OHIO, ASSIGNOR TO MODERN FOUNDRY COMPANY,
OF CINCINNATI, OHIO, A CORPORATION OF OHIO.

MOLDING.

Application filed June 21, 1927. Serial No. 200,487.

This invention relates to improvements in molding and has particular reference to an improved structure of flask.

Prior to the present invention difficulties 5 have been experienced in properly retaining the mold sand within the flask, especially in those types of flask having straight side walls adapted to be used either individually or in superimposed sections according to the 10 size of casting to be produced.

Attempts have been made to aid in retaining this sand by the employment of fins, ribs or the like projecting interiorly of the flask. These have been objectionable, however, due to distortion of the sand and consequent unequal thickness thereof and have tended to produce chill spots, indentations or other defects in the finished casting.

It is therefore the object of the present invention to provide an improved flask structure for the satisfactory retention of molds which will not deleteriously affect the castings produced therein.

A further object of the present invention 25 is the provision of a structure, such that the interior of the several flask sections will present a relatively straight and uniform wall and there will be no inequalities due to irregular inward projections or the like.

Other objects and advantages of the present construction should be readily apparent 30 by reference to the following specification taken in conjunction with the accompanying drawings, and it will be understood that 35 any modifications may be made within the scope of the appended claims without departing from or exceeding the spirit of the invention.

Figure 1 is a perspective view of a combined sectional flask embodying the present 40 improvements.

Figure 2 is a vertical sectional view as on the line 2-2 of Figure 1, and

Figure 3 is a fragmentary section as on the line 3-3 of Figure 2.

In the drawings the number 10 designates 45 the main side wall of the mold flask section, having the upper and lower outwardly extending flange portions 11 connected by bracing ribs 12. The sections may be further connected and braced as by the transverse bars 13. It will be understood that the sections here illustrated may be used as individual independent mold sections or may be com-

bined when greater height is desired. In 55 the event of combination the flange 11 are suitably secured together as by the U-clamps 14 and interposed wedges 15 or in other suitable manner.

Primarily the present invention relates to 60 the means for retaining the packed sand or mold in position within the flask. This means as is clearly illustrated in Figures 2 and 3 comprises a series of flat wedge shaped projections 16, formed on the interior of the 65 flasks with their bases at what is normally the lower edge of the flask. These wedge members as shown are preferably disposed intermediate the bars 13. They extend inward but a short distance from the face of 70 wall 10 of the flask and being of equal thickness will form a substantially continuous sand retaining projection as indicated in Figure 2, so far as the vertical plane is concerned.

At the same time they provide the downwardly converging faces 17 between which the sand is packed so that so long as the particles in general adhere, the mold as an entirety cannot become loosened or moved 80 downward relative to the flask. Also, on account of the wedge formation any slight settling merely more firmly holds the bars in place, tending to compress them rather than cutting free as would inwardly extending 85 fins.

It will also be understood that on account of the construction shown the flasks may be readily cleaned and entirely freed 90 from sand when desired and that when inverted the mold may be readily shaken free therefrom.

It will be understood that in use the complete sectional flask which has been placed over the pattern 18 is inverted or turned upside down, so that the bars 13 are then located at the base of the structure aiding in retaining the packed mold within the flask. In this event the wedge formation of the members 16 supplements the action of the 95 bars 13. The projecting portions 19 at the base of the wedges extending laterally beyond the apexes of the adjacent members provide shoulders interlocking with the packed mold sand.

I claim:—

1. A mold flask comprising a wall portion having formed on the inner face thereof a

plurality of projections of uniform thickness of substantially wedge shaped formation.

2. A mold flask comprising a wall portion having formed on the inner face thereof a plurality of projections of uniform thickness of substantially wedge shaped formation, the several wedges having their bases disposed in the same direction to provide adjacent converging retaining walls.

3. A sectional flask structure for molding, comprising a plurality of flask sections having outwardly extending attachment flanges, said sections having inwardly projecting wedge members arranged in overlying position to provide a continuous staggered mold retaining wall.

4. A flask for molding purposes, comprising a wall member having a plurality of equal thickness projections formed on the inner face thereof, said projections being of non-uniform width to provide retracted areas therebetween preventing accidental disengagement of a packed mold.

5. A mold flask of the nature described, including a circumscribing wall portion having transverse connecting members at one edge thereof and having its face formed with projections increasing in width at points remote from the connecting members.

6. A mold flask of the nature described, including a circumscribing wall portion having transverse connecting members at one edge thereof and having its face formed with projections increasing in width at points remote from the connecting members, said projections being disposed in staggered relation as respects the connecting members.

7. A sectional flask for molding purposes, comprising a plurality of members adapted to be located in super-imposed relation, said members each being formed with wedge shaped retaining projections whereby the pieces of the wedges will form mold retaining shoulders when the sections are assembled.

In testimony whereof I affix my signature
PHILIP H. CONE
